TOY DUCK

Robert Y. Allen and Melvin Shaw, Los Angeles, Calif.,
assignors to Hoover Products, Inc., Youngstown, Ohio,
a corporation of Ohio

Filed Dec. 11, 1959. Ser. No. 58,641

Term of patent 14 years

(Cl. D34—2)

FIG. 1

The side of the toy duck not shown is a mirror image of the side illustrated.

We claim:

The ornamental design for a toy duck as shown, and described.
